(57) **CLAIM**

The ornamental design for a laser level as shown and described.

DESCRIPTION

FIG. 1 is a front, right, and top perspective view of a laser level, showing my new design;

FIG. 2 is rear, left, and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the laser level and form no part of the claimed design.
